CARL M. WHEELOCK, OF MILWAUKEE, WISCONSIN, ASSIGNOR TO NEW PROCESS SPECIALTY COMPANY, A CORPORATION OF WISCONSIN.

BUSHING FOR ELECTRIC TUBULAR INSULATION.

1,204,625.

Specification of Letters Patent. Patented Nov. 14, 1916.

Continuation of application Serial No. 758,746, filed April 4, 1913. This application filed April 30, 1915.
Serial No. 24,840.

To all whom it may concern:

Be it known that I, CARL M. WHEELOCK, of Milwaukee, Wisconsin, have invented a Bushing for Electric Tubular Insulation, 5 of which the following is a specification.

My invention relates to means for holding in place at outlets and other points a flexible tubing for electric wires such as that known to the trade as "circular loom," 10 being a tube woven of textile materials and saturated with insulating compounds.

My object is to provide a means for securely attaching the tubing to the edges of openings such as those in cutout boxes, the 5 wall of which is a thin metal plate; and to provide a means which is readily put in place without the use of tools, but cannot become loose or detached of itself.

Further, I aim to provide such a device as 10 will not puncture or injure the tubing, and will protect it from abrasion on the sides of the opening.

Further, I aim to produce a device which can be produced and marketed at a trifling 5 cost.

The design of my device can be made such that it is removable or non-removable as desired without the use of tools.

The nature of my invention is best illustrated in the accompanying drawings wherein—

Figure 1 is a perspective view of the bushing; Fig. 2 is a longitudinal section through the plate and the center of a circular hole therein, showing the tubing passing through the hole and my device in position; the device shown in this figure being of the non-removable type; and Fig. 3 is a side elevation, with one side in section, of a bushing shown separately, that here shown being of the removable type.

In these drawings each reference letter or numeral refers to the same part wherever used.

The device, the two forms of which are designated respectively, α and α' in the drawings, is made in one piece, formed of sheet metal and split along one side as shown at b . It is of such diameter as to fit neatly over the "circular loom" or other flexible tubing c , which latter is shown passing through the side d of an outlet box or other opening and contains an electric wire e . Around the periphery near the middle of its length, and

preferably closer to one end than the other, 55 is formed a channel-shaped depression or groove f the width of which is substantially equal to the thickness of the metal d surrounding the hole, or slightly greater. The bottom of this channel is made preferably 60 parallel to the axis, and one edge thereof g , (the left hand edge in the drawing) substantially at right angles thereto. The bushing is made barrel-shaped, converging at the ends so that this depression has an 65 inside diameter greater than the outside of the flexible tubing c and stands away from the latter; and the two ends of the bushing rest upon the tubing as shown. One end of the bushing, that adjacent to the rectangular 70 edge g (on the left of Figs. 2 and 3) has an inwardly turned edge h , which is brought to a sharp edge, or is provided with a number of sharp points or teeth h' as preferred, which bite into the tubing sufficiently to engage firmly therewith and prevent it from slipping longitudinally. The other end of the bushing is preferably plain, and the surface from this end of the groove f is conical, or tapers on a slight angle. 75

The bushing is made of resilient metal and the bottom of the depression f when the bushing is free stands at a slightly greater diameter than that of the hole in the plate d . In order to place it in position, the bushing 80 is simply slipped over the tubing c to the proper point (being held apart if necessary sufficiently to enable the teeth or sharp edge h to slide over it), and the bushing is then pushed into the hole from the left hand side of Fig. 2. The end of the bushing is of 85 such diameter as to readily pass into the hole, and as the bushing is pushed in the edge of the hole presses the bushing together and causes the teeth or sharp edge h to bite thereinto, at the same time pressing down the bushing resiliently until the depression f snaps into the hole and engages with the sides thereof, and will be held in 90 such position by the resiliency of such depression so that the tubing cannot be moved either way. 95

If now it is desired to make the bushing non-removable, the right hand edge i of the depression f is made at right angles to the 100 axis as shown in Fig. 2; but if the bushing is to be removable, it may be made sloping as shown at i' in Fig. 3. The bushing in Fig.

2 could still be removed by using a special tool or appliance to compress the bushing, but the bushing in Fig. 3 can be removed without any tool by simply forcing it longitudinally toward the left against the side of the hole, but it is understood that the slope would be such as to require more force than any tendency of the tubing to move would exert. It will, of course, be understood that the bushing as shown is capable of being slid into the hole in the plate *d* from either direction, as in the drawing both ends of the bushing are made conical; but it is not necessary to adhere to the precise form or dimension shown, and modifications within the scope of my invention will readily suggest themselves to those skilled in the art.

I claim as my invention:

- 20 1. A self-sustaining device of the class and for the purpose described, comprising a normally-expanded tubular member slotted along one side throughout its length and having intermediate its ends two opposite facing abrupt abutment-faces to prevent longitudinal movement of the member when engaged in an opening, there being also inclined surfaces leading from the ends of said member to the top of the respective abutment-faces thereby causing the member to be circumferentially compressed by endwise movement of said member by engagement with the walls of an opening which latter has a diameter smaller than the greater diameter of said tubular member, said tubular member being frictionally retained with the said abutment faces embracing the said walls by the outward expansion of said member, substantially as described.
- 30 2. A device of the class and for the purpose described, comprising a tubular member slotted along one side throughout its length and having intermediate its ends two oppositely facing abrupt abutment faces to prevent longitudinal movement of the member when engaged in an opening, said member having at one end an inwardly projecting circumferential edge to bite into a tube held in said member, substantially as described.
- 40 3. A device of the class and for the purpose described, comprising a barrel-shaped tubular member slit along one side and having some compressive resiliency, said member having intermediate between its ends two oppositely facing abrupt abutment faces separated from each other by the thickness of a plate into a circular hole in which said

member is adapted to fit, and said faces being adapted to engage opposite sides of the plate, thereby preventing the bushing from longitudinal motion in said hole when it is placed therein with said abutment faces on opposite sides thereof; there being also inclined surfaces leading from the ends of said member to the top of the respective abutment faces, thereby causing said member to be circularly compressed when it is pushed longitudinally into said hole; and an inturned biting flange adapted to be depressed into and immovably engage the material of an insulating conduit, substantially as described.

4. A device of the class and purpose described, comprising a resilient tubular member slotted along one side throughout its length and having two oppositely facing abrupt abutment faces spaced apart a relatively short distance compared with the length of the member and adapted to prevent longitudinal movement of the member when engaged in an opening, said member having an inwardly projecting portion adapted to bite into a tube held in said member substantially perpendicularly to the surface of said tube.

5. A device of the class and purpose described, comprising a resilient tubular member slotted along one side throughout its length and having intermediate its ends two oppositely facing abrupt abutment faces to prevent longitudinal movement of the member when engaged in an opening, said member having an inwardly projecting portion adapted to bite into a tube held in said member, substantially perpendicularly to the surface of said tube.

6. A device of the class and purpose described, comprising a resilient tubular member slotted along one side throughout its length and having two oppositely facing abrupt abutment faces spaced apart a relatively short distance compared with the length of the member and adapted to prevent longitudinal movement of the member when engaged in an opening, said member having portions projecting inwardly from the body of said member adapted to bite into a tube held in said member.

In testimony whereof I have hereunto signed my name in the presence of the two subscribing witnesses.

CARL M. WHEELOCK.
